UNITED STATES PATENT OFFICE.

JOHN REICHERT, OF RACINE, WISCONSIN.

DISPLAY-RACK.

1,137,900.

Specification of Letters Patent.

Patented May 4, 1915.

Application filed February 21, 1914. Serial No. 820,253.

To all whom it may concern:

Be it known that I, JOHN REICHERT, a citizen of the United States, residing at Racine, in the county of Racine and State of Wisconsin, have invented certain new and useful Improvements in Display-Racks, of which the following is a specification.

This invention relates to certain improvements in display racks; and the objects and nature of the invention will be readily understood by those skilled in the art in the light of the following explanation of the accompanying drawings illustrating what I now believe to be the preferred embodiment from among other formations and arrangements within the spirit and scope of my invention.

The invention consists in certain novel features of construction and in combinations and arrangements as more fully and particularly pointed out hereinafter.

Referring to the accompanying drawings:—Figure 1, is a perspective view of the rack applied. Fig. 2, is a vertical section on an enlarged scale of the upper portion thereof. Fig. 3, is a vertical section on an enlarged scale of the lower portion thereof. Fig. 4, is a cross section on an enlarged scale.

The rack comprises an elongated comparatively strong heavy straight integral section of pipe adapted to extend approximately from the floor to the ceiling, and forming a vertical rotary shaft 1. This pipe is upheld by and is rotatable on a suitable step block or bearing fixed to the floor and centering the lower end of the pipe and maintaining the same against lateral deflection. This block is preferably formed in one piece and consists of a flat base 2, adapted to rest horizontally on and be fixed to the floor and a cylindrical boss 3, rising vertically from the base and having a reduced cylindrical vertical upper end 4, forming a flat horizontal annular ledge or shoulder 5, intervening between the cylindrical portions 4 and 3. The boss extends up into the lower end of the pipe and centers the same while the flat horizontal lower edge of the pipe rests and turns on the ledge 5, or on the upper face of the base around the cylindrical portion 3, according to the diameter of the pipe employed. The single bottom bearing block can hence be employed for a comparatively small pipe where a comparatively short pipe is to be employed for a compara-

tively low ceiling, and also for a larger pipe where a heavier rack is to be built for a higher ceiling. The upper end of the pipe-shaft is held properly centered and against lateral deflection, by a rigid vertical elongated post 6, depending longitudinally a considerable distance into the upper end of the pipe so that the pipe can be moved vertically thereon to accommodate ceilings of different heights or should the floor or ceiling sag. This post is rigid with a bracket or plate 7, horizontally secured to and against the ceiling. The internal diameter of the pipe 1, is considerably greater than the external diameter of the post 6, and hence to properly center the pipe on the post and to reduce friction and wear between the post and pipe, I provide a reducing cap, sleeve or nipple 8, fixed exteriorly on the upper end of the pipe and having an internal flange 9, above the top edge of the pipe providing a reduced bearing opening for and snugly receiving the post so that said flange provides the bearing between the pipe and post and maintains the post from rubbing contact with the interior of the pipe. The one size of post can be employed with various sizes of pipes by providing each pipe with a reducing cap at its upper end with a top bearing opening of the proper size to receive the post. If so desired, the lower end of the post within the pipe can be provided with a removable centering disk 10, to engage the inner surface of the pipe and thereby aid in centering the pipe and holding the same against lateral deflection.

The heavy pipe forming the rotary vertical shaft is provided with vertical series of uniformly arranged radiating arms to carry harness and parts thereof, blankets and other stock commonly found in harness shops and the like. For instance, I show the pipe shaft formed with a longitudinal series of cross holes drilled diametrically therethrough. Each hole is preferably arranged at right angles to the next adjacent holes above and below. Each hole is of a size to snugly receive a comparatively small cylindrical straight rod or pipe section and to permit such rod or pipe to be slipped therethrough so as to be arranged diametrically of the shaft and form equal or balanced horizontal radiating arms 11. The outer ends of these arms can be closed by plugs inserted and secured therein and forming exterior stops 12,

to aid in holding articles from slipping from the arms and also to aid in stiffening the arms. These plugs are applied after the arms have been slipped through the rotary 5 shaft. Each arm is securely clamped to and in the rotary shaft by a headless screw 13, screwing through a tapped radial hole in the shaft and at its inner end tightly abutting against the center portion of the arm 10 within the shaft. The outer ends of the screws 13, are preferably flush with the outer surface of the shaft.

The pipes forming the shafts can be drilled from the arms and clamping screws 15 and have reducing caps applied thereto and thus kept in stock. The arms can be kept in stock. The top and bottom bearing brackets can be kept in stock. The pipes to form the shafts can be cut to approximately the 20 lengths required for ceilings of various heights. The parts for a rack can be packed into comparatively small space and can be thus shipped knocked down, and yet the parts of the rack can be easily assembled 25 and set up in the store without requiring expert assistance.

What I claim is;

1. A harness rack adapted to be shipped knocked down and to be set up extending 30 from floor to ceiling and to accommodate ceilings of different heights, consisting essentially of a hollow vertical rotary shaft provided with vertical series of radiating arms, the upper end of said shaft projecting 35 upwardly a substantial distance above the topmost arm, a reducing cap fixed on the upper end of said shaft, a block adapted to be fixed to the floor and having an annular top bearing shoulder to removably receive 40 the lower end edge of said shaft and a vertical centering boss to removably enter the lower end of the shaft, and a ceiling bracket adapted to be fixed to the ceiling and having a rigid elongated vertical post depending a substantial 45 distance into the upper end of said shaft and on which said shaft is longitudinally movable in applying its lower end to and releasing the same from said boss and to accommodate 50 ceilings of different heights, said post being of reduced diameter with respect to the interior of said shaft, said cap forming the shaft bearing on the post.

2. A harness rack consisting of a pipe 55 forming a vertical rotary shaft, a cap on the upper end of said shaft having a reduced vertical bearing opening, a floor plate to receive the lower end of said shaft, a ceiling plate having a vertical post depending 60 through said cap opening and into the upper end of said shaft, said post being of re-

duced diameter with respect to the internal diameter of said shaft and being vertically movable thereon, and radial arms fixed to 65 said shaft.

3. A rack consisting of a pipe forming a vertical rotary shaft, a floor block having a vertical boss entering the lower end of said shaft, a ceiling plate having a post of reduced diameter depending longitudinally 70 into the upper end of said shaft, a disk on the lower end of said post within said shaft, a cap on the upper end of said post having a reduced bearing for said post, and arms fixed to and radiating from said shaft. 75

4. A harness rack adapted to be shipped knocked down and to be set up extending from floor to ceiling and to accommodate ceilings of different heights, consisting essentially of a hollow vertical rotary shaft 80 provided with vertical series of radiating arms, a block adapted to be fixed to the floor and having an annular top bearing shoulder to removably receive the lower end edge of said shaft and a vertical centering boss to 85 removably enter the lower end of the shaft, and a ceiling bracket adapted to be fixed to the ceiling and having a rigid elongated vertical post depending a substantial distance into the upper end of said shaft and 90 on which said shaft is longitudinally movable in applying its lower end to and releasing the same from said boss and to accommodate ceilings of different heights.

5. A harness rack adapted to be shipped 95 knocked down and to be set up extending from floor to ceiling and to accommodate ceilings of different heights, consisting essentially of a hollow vertical rotary shaft having a vertical series of arms extending 100 diametrically therethrough and arranged at various angles, and projecting radially in opposite directions from the shaft, the upper end of said shaft projecting a substantial distance upwardly above the topmost 105 arm, a bearing block adapted to be fixed to the floor for the lower end of said shaft, and a ceiling bracket adapted to be fixed to the ceiling and having a rigid elongated vertical post depending a substantial distance 110 into the upper end of said shaft and on which said shaft is longitudinally movable in applying its lower end to and releasing the same from said boss and to accommodate 115 ceilings of different heights.

In testimony whereof I affix my signature in presence of two witnesses.

JOHN REICHERT.
